COLLAPSIBLE STRIP FOLDERS

William J. Edwards, Stratford, Conn., assignor to The Singer Manufacturing Company, Elizabeth, N. J., a corporation of New Jersey

Application June 17, 1952, Serial No. 294,032

19 Claims. (Cl. 112—147)

This invention relates to attachments for sewing machines and more particularly to an improvement in strip-folding and guiding devices of the type having provision for deflecting or "collapsing" the strip out of the path of the sewing needle.

It is a principal object of this invention to provide a novel and improved strip-collapsing device by which it is capable of shifting a folded strip into or out of collapsed position more rapidly and in a more positive manner than has been heretofore possible.

It is a further object of this invention to provide a strip-collapsing device of the above character in which the frictional drag which is exerted upon the strip is not materially increased when the guides are shifted into strip-collapsing position.

Strip-collapsing devices are most frequently utilized in conjunction with multiple needle sewing machines arranged to secure a strip of material to one or more panels of body fabric. A typical application of such an arrangement is the banding operation of overall construction in which the bib and trouser portions are secured together by means of a reinforcing strip.

Where the garment edges are to be subsequently hemmed, as in the usual garment construction, a seam including a reinforcing strip with infolded marginal edges presents the difficulty that the hem-folds at the point of intersection of the hem with the reinforced seam will be of prohibitive bulk, i. e. will contain such a large number of fabric thicknesses as to be practically impenetrable by the needle used in the hemming operation. Strip-collapsing folders are used as a convenience in reducing the bulk of the reinforced seam at points which will subsequently be hemmed. The folder acts to deflect or collapse the reinforcing strip out of the line of strip securing stitches so that the strip may be severed just short of the hem without the necessity for tedious removal of the strip securing stitches by hand.

In the instant invention the principal objects of rapid and positive shifting of the strip and of the reduction in frictional drag on the strip when in collapsed position are accomplished by means of a shiftable arbor about which the strip margins are folded. When the strip is collapsed, the arbor is retracted, thus acting to prevent binding of the strip in the guide. When the guide is returned to normal position, the arbor is shifted to operative position and in so shifting acts to force the strip margins quickly and positively into normally extended position.

It is also an object of the present invention to provide a novel and improved mechanism by which movements of the strip-collapsing members and the arbor may be accomplished in a predetermined relative sequence.

A still further object is to provide a novel manually operable actuating linkage for the strip-collapsing device which linkage may, with a minimum of adjustment, be adapted for use when the machine to which it is attached is supported in the usual manner directly upon a sup-

2

porting table, or equally well when the machine is supported upon an elevated sub-base.

With the above and other objects and advantages in view as will hereinafter appear, the invention comprises 5 the devices, combinations and arrangement of parts hereinafter described and illustrated in the accompanying drawings in which:

Fig. 1 is a front elevational view of a portion of a sewing machine having the invention applied thereto and illustrating a form of actuating linkage particularly adapted for use when the sewing machine is supported directly upon a supporting table in the usual manner.

Fig. 2 is a top view of the strip-collapsing folder and actuating linkage of Fig. 1 in which only a portion of the machine frame is illustrated and in which a portion of the slide plate together with the body fabric guides have been removed to expose the strip-collapsing devices.

Fig. 3 is a bottom view of the strip guide and that portion of the strip-collapsing mechanism which is carried by the sewing machine slide cover plate.

Fig. 4 is a fragmentary view in front elevation of a sewing machine frame illustrating a sub-base support and a modified form of actuating linkage for strip-collapsing mechanism particularly adapted for use with the sub-base.

Fig. 5 is a cross sectional view taken lengthwise of the strip-collapsing folder substantially on line 5—5 of Fig. 2.

Fig. 6 is a cross sectional view of the strip-collapsing folder taken substantially on line 6—6 of Fig. 2.

Fig. 7 is a cross sectional view of the strip collapsing folder taken substantially on line 7—7 of Fig. 2.

Fig. 8 is a cross sectional view of the strip-collapsing folder taken substantially on line 8—8 of Fig. 2.

Fig. 9 is a fragmentary detached top view of the delivery end of the strip guide showing a fabric strip issuing from the guide with the strip-collapsing member arranged in strip-collapsing position.

Fig. 10 is a fragmentary detached top view similar to Fig. 9 but showing the position of the parts and of a strip of fabric immediately after the strip-collapsing member has been returned to normal position.

Fig. 11 is a disassembled view showing the strip guide stiffening strip in bottom plan view with the strip-collapsing members attached thereto, and the actuating slide-plate for the strip-collapsing members together with its guide block removed, turned back and illustrated in perspective view.

In the drawings, my improved strip-collapsing folder is illustrated as applied to a three needle chain-stitch sewing machine having a frame including a bed 11 formed with a work-support 12 and a standard 13 rising from the bed, from which a bracket-arm (not shown) extends over the work-support. Journaled in the bracket-arm is the usual reciprocatory needle-bar 14 to which spaced needles 15 are secured. Also carried by the bracket-arm is a downwardly biased presser-bar 16 fitted at the lower extremity with a presser-foot 17 which is opposed to a throat-plate 18 carried by the work-support. Supported in the bed 11 beneath the work-support 12 is a work-feeding mechanism including a feed-dog 20, which is operable through slots 21 in the throat-plate below the presser-foot 17. Also carried beneath the work-support are the usual oscillatory thread-carrying loopers (not shown) which are complementary to the needles 15 in the formation of chain stitches. To facilitate threading of the loopers and the like, the work-support is formed with an access aperture 25 which is normally closed by a slide cover-plate 26.

In the present invention, the strip-guiding and collapsing instrumentalities, actuating means therefor, and the usual guiding and manipulating instrumentalities for opposed plies of body fabric are carried by the slide-cover plate 26 for ready removal from and replacement there-

with on the sewing machine. A manually operable linkage for imparting movement to the actuating mechanism is secured to the machine bed 11, a slidable interlocking connection being provided therebetween, as will be described more fully hereinafter, thus making it possible to ready the sewing machine for a strip-collapsing operation by the mere substitution for the ordinary slide-plate of one to which is affixed a strip-collapsing folder constructed in accordance with this invention. As shown in Fig. 1, an edge guide 27 for one ply of body fabric and an edge folding guide 28 for a second ply of body fabric are secured to the upper surface of the slide cover-plate 26.

Referring more particularly to Figs. 2 and 3, the slide cover-plate 26 is cut away at 30 to embrace the throat-plate 18 and to accommodate the delivery end of a strip guide which is indicated generally as 31. The strip-guide includes a flat sheet metal base portion 32 of which each side is gradually inturned from the strip-receiving end to the delivery end to form opposed edge-folding scrolls 33, 33 at the delivery end of the guide. Secured to the in-turned portions 33—33 and extending laterally one at each side of the strip-guide, are supporting members 35—35 which seat against an angle bracket 36 fixed to the under surface of the slide cover-plate. By means of slot and fastening screw connections 37—37 therebetween, the strip-guide is secured for limited lateral adjustment in an upwardly inclined position beneath the slide cover-plate.

Secured in spaced relation with the base portion 32 of the strip-guide at the strip-receiving end thereof, is a strip smoothing and confining spring-tongue 39 provided with a longitudinal slot 40 through which any suitable pointed instrument may be passed to facilitate insertion of a strip into the guide in the usual manner. The free extremity of the tongue 39 extends between the base portion 32 of the strip-guide and a bridge piece 41 which is secured between the in-turned portions 33—33 at the delivery extremity of the guide. The bridge piece 41 is formed with a longitudinal guide slot 42 which accommodates an up-standing guide block 43 carried by a shiftable arbor member 44. The side edges 45—45 of the arbor member 44 are arranged to extend each within one of the in-turned portions of the strip-folding scrolls 33—33 at the delivery end thereof, thereby to provide shiftable arbors about which the edges of the strip will be folded. Figures 6, 7 and 8, which are cross-sectional views of the strip-guide near the strip-receiving extremity, at a mid-point and at the delivery extremity respectively, best illustrate the relationship of the above described parts. Fig. 6 shows clearly that the shiftable arbor member 44 extends at one end between the bridge piece 41 and the spring tongue 39 so that the strip will not snag on the arbor. Snagging is also minimized by the tapered form of the side-edges 45—45 of the arbor 44, as illustrated in Fig. 2. Referring to Fig. 7 the edge folding scrolls 34—34 are completely formed near the delivery end of the guide and comprise in addition to the in-turned strip-folding portion 33—33, infolded arbor portions 46—46 which extend within the in-turned portion 33 and provide stationary arbors one at each side about which the edges of the strip are folded. Side edges 45—45 of the shiftable arbor member 44 are disposed to underlie and supplement the stationary arbor portions 46—46 as will hereinafter be described more fully.

Carried by an auxiliary stiffening plate 50 which is secured beneath the strip guide 31, are opposed right and left hand strip-collapsing members 51, 51' and an actuating mechanism therefor. These parts are best illustrated in Figs. 3 and 11. Since the strip-collapsing members are similar and merely of the opposite hand, like numbers will be used to indicate like parts of each, prime numbers, however, will be used to designate the parts of the right hand member as viewed in Fig. 3. Each strip collapsing member comprises a plate 52, 52' pivoted as at 53, 53' beneath the stiffening-plate 50 and

provided with an upstanding strip-engaging finger 54, 54' which extends forwardly in advance of the delivery end of the strip guide. The upper edge of each of the opposed strip-engaging fingers 54, 54' is formed with a flange 55, 55' which extends inwardly in spaced strip-confining relation with the respective plate 52, 52'. The position of each of the strip-collapsing members 51, 51' is controlled by means of a slide-plate 56 which is confined for movement lengthwise beneath the strip-guide by a channeled block 57 secured to the stiffening strip 56 by screws 57'. The slide-plate 56 extends forwardly to underlie the plates 52, 52' and as best illustrated in Fig. 11 is formed beneath the plates with spaced longitudinal slots 58, 58', each slot terminating in cam surface 59, 59' which surfaces are transversely aligned. A pair of blocks 60, 60' are secured for limited lengthwise adjustment beneath the slide-plate 56 by means of fastening screws 61, 61' and slots 62, 62' each block being formed with an upturned lug 63, 63' arranged to enter the slots 58, 58' to provide transverse cam-surfaces 64, 64' which are longitudinally opposed to cam surfaces 59, 59' respectively. Depending from each of the plates 52, 52' of the strip-collapsing member is a pin 65, 65', arranged between the cam surfaces 59, 59' and 64, 64'.

The slide-plate 56 is normally biased forwardly by spring 70 to a position determined by a lug 71 and the channeled block 57. In this normal position as illustrated in Fig. 3, the aligned cam surfaces 59, 59' of the slide-plate engage pins 65, 65' respectively and urge the strip-collapsing members into extreme separate position one at each side of the normal path of a strip beyond the delivery end of the strip guide. By means of a depending pin 72, slide plate 56 may be shifted rearwardly in opposition to spring 70. When so shifted, the cam surfaces 64, 64' engage the pins 65, 65' as shown in Fig. 9 and serve to shift the strip-engaging members transversely of the strip guide about the respective pivots 53, 53' and into operative position as illustrated in Fig. 9 and also in dot and dash lines in Fig. 3, in which the strip-engaging fingers 54, 54' occupy positions within the normal path of the strip as it issues from the delivery end of the guide. As shown in Fig. 9, the strip-engaging fingers 54, 54' may be shifted to converge and collapse the strip to a position between the needles and out of the lines of stitching produced by the needles at each side of the strip which is indicated as S. Simultaneously, the arbor member 44 is retracted to a position preferably within the strip folding guide so that binding of the fabric strip between the arbor and the in-turned strip-collapsing member is minimized. Fig. 10 illustrates the manner in which the work-engaging parts affect the fabric strip immediately after the parts have been returned to normal operating position. The strip-engaging fingers 54, 54' are turned outwardly to a position substantially parallel to the path of travel of the strip, and the arbor member 44 is returned to its forward position in which the side edges 45—45 thereof are disposed in work controlling relation opposite the strip-engaging fingers 54, 54'. In this position of the arbor member, the folded edges of the fabric strip are urged outwardly in a positive manner into normally extended position at a point longitudinally of the guide closer to the needles than would be otherwise possible. As a result, the transition in the stitched strip from collapsed position to the normally extended position is accomplished in a shorter length of the strip, and, consequently, the distortion of the strip due to the transition is minimized.

Since the relative position of the blocks 60, 60' and consequently of the cam surfaces 64, 64' may be adjusted longitudinally by means of screws 61, 61', the extent of operative movement of each strip-engaging member may be varied independently. As shown clearly in Figs. 3 and 11, the block 60' is positioned forwardly

of the block 60 on the slide plate 56. Correspondingly, the lug 63' and the cam surface 64' formed thereby is positioned forwardly of the counterparts 63 and 64 of block 60. As a result, lost motion occurs between pin 65' and cam surface 64', as illustrated in Figs. 9 and 10, and consequently, a smaller transverse movement of the strip-collapsing member 51' is produced. This convenient and simple adjustment of strip-collapsing motion is useful, for instance, where a greater number of needles or a wider needle gauge is employed to secure one side of the strip than the other. With the instant adjustment, the blocks 60 and 60' may be positioned in laterally aligned arrangement thereby providing for an equal movement of the strip collapsing members. It is also possible to position one of the blocks 60, 60' sufficiently far forward so that the corresponding strip-engaging member is rendered completely inoperative. Such adjustment is useful where it is desired to collapse only one side of the strip.

In the present construction means are provided for actuating the strip-collapsing members 51-51' and the shiftable arbor member 44 in a timed relationship such that the strip may be collapsed without any appreciable increase in the frictional drag exerted thereon and may be quickly restored to normal extended position in a more positive manner than has been heretofore possible.

Extending from the channeled block 57 beneath the strip-guide, is a supporting arm 80 to the extremity of which is pivoted a lever 81. Carried by the lever 81 are spaced lever arms 82 and 83. The lever arm 82 extends beneath the strip guide and is formed with an arcuate slot 84 which embraces the pin 72 depending from the slide-plate 56. The lever arm 83 extends above the strip-guide and is formed with a radial slot 85 which embraces a pin 86 secured in the guide lug 43 of the arbor member 44. The lever 81 is provided with a follower pin 100 by which movement may be imparted to the lever 81 by a linkage carried by the machine bed as will be described hereinafter.

A spring 87 is arranged between the lever 81 and the stiffening plate 50 on the strip-guide to bias the lever into the normal position illustrated in Fig. 3, in which the strip-collapsing members are disposed out of the path of the strip and the shiftable arbor member 44 is extended forwardly in advance of the delivery end of the strip-guide as shown in Fig. 10.

When the lever 81 is shifted to collapse the strip, the initial movement of the lever results only in a retraction of the arbor member 44 by means of the lever arm 83. The strip-collapsing members remain unaffected by the initial movement of the lever because of the arcuate slot 84 in the lever arm 82 which provides a lost motion connection between the lever arm and the slide-plate 56. The advantage of the sequence of motion provided by this construction is that the arbor member is thereby positioned to provide maximum control over the work during normal operation, while immediately preceding collapsing of the strip the arbor is retracted to prevent pinching or binding of the strip and, consequently, reducing the frictional drag exerted on the strip when in collapsed position.

On continued movement of lever 81, the pin 72 of the slide-plate 56 is engaged by the lever arm 82 and is shifted rearwardly. The cam surfaces 64, 64' then engage pins 65, 65' of the strip-collapsing members either simultaneously or in timed sequence depending upon the relative position of adjustment of the blocks 60, 60', as described in detail above. As illustrated in the position of adjustment of Figs. 9 and 10, surface 64 first engages pin 65 and begins to turn the left hand strip-collapsing member 51. The additional lost motion between cam surface 64' and pin 65' delays initiation of movement of the right hand strip-collapsing member 51', and thereby results in a smaller extent of movement thereof, as is shown clearly in Fig. 9.

When the lever 81 is returned to normal position the reverse sequence of movement occurs, that is, the strip-engaging members are first returned to normal position out of the path of the strip and then the arbor member 5 is forced outwardly in advance of the delivery end of the strip guide. In being shifted forwardly, the side edges 45, 45 of the arbor member 44 engage the infolded sides 10 of the collapsed strip and positively force the folded strip to reassume the normal extended position opposite the strip-engaging fingers 54, 54'. Due to the positive nature 15 of the control exercised over the strip during the collapsing operation the complete transition from normal to collapsed position of the stitched strip and vice versa occurs within fewer stitches than has been heretofore possible with usual strip-collapsing devices, and therefore, distortion of the resulting seam is minimized.

The actuating linkage will now be described by which movements may be imparted to the lever 81 to collapse the strip at the will of the sewing machine operator. As 20 illustrated in Figs. 1, 2 and 4 a vertically disposed support plate 90 is arranged in spaced relation to the bed 11 by means of turned portions 91-91 by which the plate is secured to the bed by fastening screws 92. Pivoted to the support plate at 93 is an actuating lever 94 which is 25 slotted as at 95 to accommodate a slidingly pivotal connection 96 with one extremity of a slide-bar 97. The bar 97 which is confined for endwise sliding movement with respect to the support plate by means of a channeled block 98, is formed at the other extremity with an upturned and outwardly extending bifurcated jaw portion 99. The jaw portion 99 opens outwardly which, as shown in Fig. 1, corresponds to the direction in which the slide-plate 26 must be shifted in the access aperture 25 of the machine work-plate in order to be removed or replaced 30 therein. A pin 100 which depends from the lever 81 is embraced by the jaw 99 when the slide-plate 26 is shifted into position in the access opening 25, and, similarly, the pin will be readily separable from the jaw when the slide-plate is removed. A coil-spring 101 is arranged between 35 the channeled block 98 and the slide-bar 97 to bias the bar 97 to the left as viewed in Fig. 1, into a position as determined by the adjustable stop block 102 carried by the bar 97. The stop block 102 is preferably positioned so as to locate the jaw 99 in alignment with the position 40 in which pin 100 is normally biased by the coil spring 87 whereby a positive interlock will be effected between the pin and the jaw each time the slide-plate 26 is replaced. A second stop-block 103 is adjustably secured to the slide-bar 97 to limit the extent of movement of the slide-bar in opposition to the spring 101 and consequently to 45 limit the extent of overall strip-collapsing movement.

In the most usual installation of a sewing machine in its supporting table or power table, as it is usually termed, the sewing machine bed extends downwardly into a cut-out portion of the supporting table so that the work-support 12 is disposed at the level of the top surface of the power table. In Figs. 1 and 4 the broken line labeled 50 105 represents the top surface of the power table in the usual installation. Where tubular work is to be stitched, it is desirable to elevate the sewing machine by means of a sub-base 106 as shown in Fig. 4. Locating pins, of 55 which one is shown at 107, depend from the machine bed and enter apertures 108 in the sub-base to firmly seat the machine in place. A resilient pad 109 may be arranged between the machine and sub-base at each of the locating pins 107 to reduce the effects of vibration. The sub-base 106 rests directly upon the power table 110, in 60 which case, as shown in Fig. 4, the elevation of the sewing machine with respect to the power-table top 105 is decidedly increased. This difference in sewing machine elevation presents the problem, where a pivotally mounted knee shifter is used, that in the elevated position, the extent of movement of the knee shifter becomes excessive. In the present construction, a knee shifter pad 111 65 is adjustably secured to the depending portion 112 of a 70 75

bent supporting rod 113. As shown in Fig. 1 and in dashed lines in Fig. 4, when the sewing machine is supported at the level of the power table top the supporting rod 113 is normally arranged in a transverse bore 114 formed in the pivoted lever 94 and is secured in place by means of a set screw 115. When the machine is elevated, the knee-shift pad may be adjusted to a lower position along the depending portion 112 of the support rod to retain a favorable elevation with respect to the sewing machine operator's knee; however, if this is done, the distance between the knee pad 111 and the pivot 93 about which it turns is increased and the movement necessary at the knee pad becomes excessive. A simple and economical arrangement has been provided in the present invention whereby this excessive movement is reduced when the machine is supported in elevated position. Pivoted to the sub-base at 120 is a bell-crank lever 121. To the horizontal arm 122 of the bell-crank is pivoted a roller 123 of which the periphery is grooved as at 124 to embrace a straight cylindrical rod 125 which is substituted in the transverse bore 114 of lever 94 in place of the knee pad supporting rod 113. A depending arm 126 of the bell-crank lever 121 is formed with a transverse bore 127 and provided with a set screw 128 in a manner identical with that of the lever 94 such that the knee-shifter supporting rod 113 may be carried either by lever 94 when the machine is supported in normal fashion or by arm 126 of the bell-crank when the machine is placed upon an elevating sub-base. The use of the bell-crank lever 121, it will be understood, favorably changes the mechanical advantage of the actuating linkage for the strip-collapsing members whereby the extent of motion of the knee pad 111 is reduced. Since the bell-crank 121 may be pivoted permanently to the sub-base, conversion of a machine support from a normal to an elevated position involves, insofar as the knee shifter is concerned, only that the knee-shifter support rod 113 be shifted from one lever to the other and that the rod 125 be fixed in place.

Having thus set forth the nature of the invention, what I claim herein is:

1. In a strip guide, a flat strip guiding portion, a strip folding scroll arranged in communication therewith, an arbor member arranged to extend in work-folding relation within said scroll, said arbor member being slidably supported for movement lengthwise of said guide, means carried by said strip guide for collapsing the strip beyond the delivery end of said guide, and means for shifting said arbor member to accommodate said strip-collapsing means.

2. In a strip guide for sewing machines, a strip-folding scroll, a shiftable arbor member disposed in work folding relation with said scroll, means limiting movement of said arbor member between a retracted position substantially coterminous with said scroll and an extended position in which said arbor member projects beyond the delivery end of said scroll, and means under control of the sewing machine operator for shifting said arbor member into retracted or extended position.

3. In a strip-collapsing attachment for a sewing machine, a fixed strip guide, strip-folding instrumentalities formed on at least one side of said strip guide, a strip-collapsing member normally disposed out of the path of the strip adjacent said strip-folding instrumentalities, means for shifting said strip-collapsing member into operative position in the path of the strip, and a retractable arbor associated with said strip guide, said arbor being disposed to extend within the fold of the strip at a point opposite said strip-collapsing member.

4. A strip-guiding device, comprising a plate, inturned strip-folding side-edge portions formed on said plate, a first pair of arbor members fixed to said plate, said arbor members disposed substantially coterminous with the delivery end of said plate and arranged to extend each within one of said inturned side-edge portions, a second pair of arbor members arranged complementary to said

first pair of arbor members and slidably supported for movement lengthwise thereof to an extended position in advance of the delivery end of said plate.

5. A strip-collapsing folder for a sewing machine comprising a strip guide including spaced edge-folding scrolls, spaced strip-collapsing members disposed one at each side of said strip guide and extending beyond the delivery end thereof, spaced retractable work controlling arbors extending one within each of said edge folding scrolls, said arbors normally disposed to extend beyond the delivery end of said strip guide, and means operatively associated with said strip-collapsing members and with said arbors for simultaneously actuating said strip-collapsing members and retracting said arbors.

6. In a strip guide, a flat strip guiding portion, a strip folding scroll arranged in communication therewith, an arbor member arranged to extend in enveloped relation with said scroll, said arbor member being slidably supported for translatory movement lengthwise of said guide, a strip-collapsing member pivotally secured to said strip guide, said member having a strip engaging portion disposed in advance of the delivery end of said strip guide, and means operatively associated with each of said members for simultaneously imparting turning movement to said strip-collapsing member and translatory movement to said arbor member.

7. In a strip-collapsing attachment for a sewing machine, a strip guide, inturned strip-folding side edge portions formed on said strip guide, an arbor plate slidably supported for translatory movement lengthwise of said strip guide and arranged to extend into enveloped relation with each of said inturned side portions of said strip guide, spaced strip-collapsing members pivotally secured one at each side of said strip guide at the delivery end thereof and means operatively associated with said strip-collapsing members and said arbor plate for simultaneously turning said strip-collapsing members in opposite directions and retracting said arbor plate.

8. In a strip guide, spaced strip-folding scrolls, a strip-collapsing plate slidably supported between said scrolls, said plate extending at each side within a respective one of said scrolls to provide spaced arbors about which the marginal edges of a strip are folded by the scrolls, spaced strip-collapsing members normally disposed one at each side of said strip guide and extending beyond the delivery end thereof, an actuating member carried by said strip guide for movement within a predetermined range, an operative connection between said actuating member and said strip-controlling plate effective to transmit movement of said plate over the entire range of movement of said actuating member, and a connection between said strip-collapsing members and said actuating member, said last mentioned connection effective to transmit movement to said strip-collapsing member during only a portion of the range of movement of said actuating member.

9. A strip-collapsing folder for a sewing machine comprising a strip guide including spaced edge-folding scrolls, spaced strip-collapsing members normally disposed one at each side of said strip guide and extending beyond the delivery end thereof, spaced work-controlling arbors extending one within each of said spaced edge-folding scrolls, means slidably securing said arbors to said strip guide for movement longitudinally thereof, an actuating lever, operative connections between said lever and said strip-collapsing members effective to shift said members transversely of said strip guide and operative connections between said lever and said work-controlling arbors effective to shift said arbors lengthwise of said guide.

10. In a strip-collapsing folder, a strip guide comprising a flat strip guiding portion, opposed strip folding scrolls arranged in communication therewith, a longitudinally slotted bridge piece spanning said scrolls and a shiftable arbor arranged between said bridge piece and said strip guide, strip-collapsing instrumentalities secured to said strip guide and arranged to extend in advance of

the delivery end thereof, and a lever pivoted to said strip guide, an arbor actuating arm carried by said lever having operative connections with said arbor through said longitudinally slotted bridge piece, a second arm carried by said lever, and operative connections between said second arm and said strip-collapsing instrumentalities.

11. In a strip-collapsing folder, a strip guide comprising a flat strip-guiding portion, a strip-folding scroll arranged in communication therewith, an arbor member slidably supported for movement lengthwise of said strip guide and arranged to extend in enveloped relation with said scroll, a strip-collapsing device comprising a work engaging member supported by said strip guide for movement transversely of said strip guide and arranged to extend in advance of the delivery end thereof adjacent said strip-folding scroll, means normally maintaining said arbor member in extended position in advance of the delivery end of said strip guide, and an actuating member carried by said strip guide and disposed in operative association with said arbor member and said strip-collapsing device, said actuating member being arranged to engage and shift in seriatim first the arbor member and then the strip collapsing device.

12. In a strip-collapsing folder for a sewing machine, a strip guide having edge-folding scrolls, a retractile arbor member slidably supported for movement lengthwise of said strip guide, spaced strip-collapsing members carried by said strip guide for movement transversely thereof, and means automatically effecting in seriatim a retraction of said arbor member and a shift of first one and then the other of said strip-collapsing members, said means comprising an actuating lever carried by said strip guide, a first and a second lever arm extending therefrom, said first lever arm arranged in continuous operative engagement with said arbor member, a block supported for endwise sliding movement with respect to said strip guide and positioned for delayed engagement by said second lever arm, and complementary abutment members adjustably secured to said block and each of said strip-engaging members.

13. In a strip-collapsing folder for a sewing machine, a strip guide having edge-folding scrolls, a retractile arbor member slidably supported for movement lengthwise of said strip guide, spaced strip-collapsing members carried by said strip guide for movement transversely thereof, and means automatically effecting in seriatim a retraction of said arbor member and a shift of first one and then the other of said strip-collapsing members, said means comprising an actuating lever carried by said strip guide, a pair of lever arms extending therefrom, operative connections between the first of said lever arms and said arbor member, a block supported for endwise sliding movement with respect to said strip guide, a pin and slot lost motion connection between the second of said lever arms and said block whereby said arbor member is substantially retracted before initial movement of said block, and adjustable pin and slot lost motion connections between said block and each of said strip-collapsing members whereby said members may be shifted in seriatim.

14. A strip-collapsing device for a sewing machine having stitch-forming instrumentalities and a frame including a work support formed with an aperture adjacent the stitch-forming instrumentalities for access thereto, said strip-collapsing device comprising a slide cover plate for said access aperture, a strip guide having spaced edge-folding scrolls carried by said slide cover plate, a retractile arbor member slidably supported by said strip guide, spaced strip-collapsing instrumentalities secured to said strip guide and arranged to extend in advance of the delivery end thereof, a lever carried by said strip guide, a first operative connection between said lever and said retractile arbor, a second operative connection between said lever and said strip-collapsing members, actuating mechanism for said lever carried by said sewing machine

frame, said actuating mechanism disposed to operatively engage said lever when said slide cover plate is positioned in said aperture.

15. In a sewing machine having a work-support, a table having a machine supporting top, means normally supporting said sewing machine from said table with said work-support substantially at the same elevation as said table top, and a sub-base adapted to be interposed between said table top and said sewing machine to elevate said work-support, a strip collapsing device carried by said sewing machine, an actuating mechanism for said strip collapsing device including an arm pivoted to said sewing machine on an axis disposed at a fixed distance beneath said work-support, a knee pad, means normally securing said knee pad to said pivoted arm, a lever pivoted to said sub-base on an axis disposed beneath the pivotal axis of said arm, said lever disposed in position to impart movement to said arm when said sub-base is interposed between said table top and said sewing machine and means for securing said knee pad to said lever.

16. In a sewing machine having a work-support, a table having a machine supporting top, means normally supporting said sewing machine from said table with said work-support substantially at the same elevation as said table top, and a sub-base adapted to be interposed between said table top and said sewing machine to elevate said work-support, a strip collapsing device carried by said sewing machine, an actuating mechanism for said strip collapsing device including an arm pivoted to said sewing machine on an axis disposed at a fixed distance beneath said work-support, a knee pad, a knee pad supporting bar, means carried by said pivoted arm and adapted to receive said bar, a bell-crank lever pivoted to said sub-base on an axis disposed beneath the pivotal axis of said arm, one arm of said bell-crank lever being disposed in position to impart movement to said pivoted arm when said sub-base is interposed between said table top, and said sewing machine, and means carried by the other arm of said bell-crank lever and adapted to receive said knee pad supporting bar.

17. In a sewing machine having a work-support, a table having a machine supporting top, means normally supporting said sewing machine from said table with said work-support substantially at the same elevation as said table top, and a sub-base adapted to be interposed between said table top and said sewing machine to elevate said work-support, a strip collapsing device carried by said sewing machine, an actuating mechanism for said strip collapsing device including an arm pivoted to said sewing machine on an axis disposed at a fixed distance beneath said work-support, a knee pad, a knee pad supporting bar, means adjustably securing said supporting bar to said pivoted arm, a lever pivoted to said sub-base on an axis disposed beneath the pivotal axis of said arm, a member adapted to be secured to said pivoted arm in place of said knee pad supporting bar, said member arranged in operative engagement with said lever when said sub-base is interposed between said sewing machine and said table top, and means adjustably securing said knee pad supporting bar to said lever.

18. In a strip-collapsing device for a sewing machine having a needle and feed mechanism for feeding work fabric past said needle, the combination comprising an arbor member disposed on that side of the needle toward which the work is advanced by said feed mechanism, means for presenting a fabric strip to said needle in folded relation about one side of said arbor member, a strip-collapsing member normally disposed adjacent said one side of said arbor member, and manually operable means operatively associated with both said arbor member and said strip collapsing member for simultaneously retracting said arbor member from said needle and shifting said strip-collapsing member to a position between said needle and said arbor member.

19. In a strip-collapsing device for a sewing machine

having a pair of needles and a mechanism for feeding work fabric past said needles, the combination comprising a bracket adapted to be secured to said sewing machine, an arbor member slidably arranged on said bracket, said arbor member being disposed on that side of the needles toward which the work is advanced by said feed mechanism, work-engaging side edge-portions formed on said arbor member, means carried by said bracket for presenting a strip of fabric to said needles in folded relation about both of the side edge-portions of said arbor member, a pair of strip-collapsing members each being disposed on that side of the needles toward which the work is advanced by the feed mechanism and each being shiftable transversely of the line of feed, said strip-collapsing members normally being disposed one adjacent each of said

10

arbor member side edge-portions, and means carried by said bracket and operatively associated with both said arbor member and said strip collapsing members for simultaneously retracting said arbor member from said needles and for shifting said strip-collapsing members each to a position between a respective one of said needles and said arbor member.
